United States Patent Office.

HAMILTON S. MCRAE, OF MUNCIE, INDIANA.

Letters Patent No. 72,662, dated December 24, 1867.

IMPROVED SCHOOL-DESK.

The Schedule referred to in these Letters Patent and making part of the same.

TO ALL WHOM IT MAY CONCERN:

Be it known that I, HAMILTON S. MCRAE, of Muncie, in the State of Indiana, have invented a certain new and useful Improvement on School-Desks, and Seats therefor; and I do hereby declare that the following is a full, clear, and exact description of the same, reference being had to the accompanying drawings, and to the letters and marks thereon, which said drawings form part of this specification, and, by the several figures thereof, show a school-desk and seat constructed under my invention, of which—

Figure 1 is a top view of the desk and seat.

Figure 2, a side view of the same.

Figure 3, a vertical sectional view of the desk; and

Figures 4, 5, 6, and 7, views in detail of the legs of the chair or seat.

In each of these figures, where like parts are shown, like marks and letters are used to indicate the parts.

My invention has for its objects providing the desks with a convenient and easily-operated book-holder, and of giving facilities, by peculiarities of construction of the legs of the desk and seat or chair, for the occupancy thereof.

In the top or lid *a* of the desk *b*, the book-holder *c* is affixed, the turning-point or pivot of it being near its front part, or that part nearest the seat or chair, as indicated at *d*, fig. 3. This book-holder is thus located far from the front part of the desk, which obviates, to a considerable extent, the tendency of the scholar or occupant to become round-shouldered and near-sighted that is apt to exist when the book-holder is nearer the front of the desk. When this book-holder is folded down, as is shown by fig. 1, there is a smooth surface on which to write, and when the holder is elevated, as shown by figs. 2 and 3, there is a space between the edge of the holder and the lid, as shown at *e*, in fig. 3, for receiving and holding the ends of the book-cover. To the under surface of the book-holder there is attached a ratchet, *f*, the centre-pin having bearings in the plates or sockets thereof, *g*. The thumb-piece *h* of the ratchet passes through the slot *i* of the book-holder, so that the raising or lowering of the holder, and the operating of the ratchet, can readily be effected by one hand only. When the holder is elevated, the lower end of the ratchet fits into the teeth or notches in the back *j* of the desk, or a plate attached thereto. When the holder is down, the lower end of the ratchet will be below the bottom of the desk, passing through a slot therein, the two conditions of the ratchet being shown by fig. 3. The legs *K* of the desk can be made by casting or otherwise, of one piece of metal for each end of the desk, and united by a cross-bar or piece, or not, as may be deemed necessary to strengthen or support the desk. The rear part of the leg is vertical, while the front part is quite curved, so that the teacher or pupil, particularly if a female, will have much easier access to the seat than when the front part of the leg is vertical, or of some other less accommodating form. By having the front part of the leg thus curved, the support given to the desk by the extending out of the lower part or foot *l*, is greater than it would be if the leg were vertical. The legs of the chair *m* and *n* can each be made of one piece, either by casting or otherwise. The front leg *m*, it will be seen, inclines rapidly in a curved line from the foot to the upper part, where it is widened out, as indicated at *o*, fig. 4, for giving a good and broad bearing for the bottom of the chair. A notch, *p*, in the leg, allows of the fitting in of the broad part *q* of the head of the leg *n*, so that the two legs at this point are quite firmly united to each other. This curving of the leg *m* of the chair or seat, like the curving of the front part of the leg of the desk, facilitates access to the desk and seat, while it also gives a firm and steady bearing and support to the chair.

What I claim as my invention, and desire to secure by Letters Patent, is—

The book-holder, located in the back part of the lid of the desk, constructed, arranged, and operated, as herein recited.

This specification signed this 26th day of October, 1867.

HAMILTON S. MCRAE.
